CLAIM

The ornamental design for a cap removal tool, as shown and described.

DESCRIPTION

FIG. 1 is a front perspective view showing my new design; FIG. 2 is a front view thereof;

FIG. 3 is a back side view thereof;

FIG. 4 is a top view thereof;

FIG. 5 is a bottom view thereof;

FIG. 6 is a right side view thereof;

FIG. 7 is a left side view thereof; and,

FIG. 8 is a front perspective view thereof, shown in an environment of use. The broken lines depict environmental structures and form no part of the claimed invention.
